UNITED STATES PATENT OFFICE

105,348

DESIGN FOR A LETTER OPENER

George R. Switall, Chicago, Ill.

Application October 16, 1935, Serial No. 59,012

Term of patent 7 years

To all whom it may concern:

Be it known that I, George R. Switall, a citizen of the United States, residing at Chicago, in the county of Cook and State of Illinois, have invented a new, original, and ornamental Design for a Letter Opener, of which the following is a specification, reference being had to the accompanying drawing, forming a part thereof.

In the drawing:

Figure 1 is a plan view of a letter opener showing my new design;

Figure 2 is a front view thereof; and

Figure 3 is an end view thereof.

The major novel feature of this design lies in the stream lined effect wherein the body of the letter opener is of progressively greater width towards one end thereof, and the sudden arrow-like taper from the widest portion to the end of the letter opener.

I claim:

The ornamental design for a letter opener substantially as shown and described.

GEORGE R. SWITALL.
